UNITED STATES PATENT OFFICE.

FREDERICK A. SCHWANNECKE, OF NEW ROCHELLE, NEW YORK.

CONTAINER.

Application filed April 28, 1927. Serial No. 187,130.

My invention relates to containers and refers particularly to devices of this character adapted for holding a plurality of toilet preparations.

5 While it is generally admitted that loose powder is more advisable for application to the skin than is powder in compact form, the use of the former has been greatly limited by the difficulty in making containers 10 which are free from leakage, while allowing ready access to the powder.

15 My device overcomes this objectionable feature and presents a container capable of carrying powder free from leakage as well as a number of other toilet preparations.

In the accompanying drawings illustrating modified forms of the device of my invention similar parts are designated by similar numerals.

20 Figure 1 is a perspective view of one form of my device in closed position.

Figure 2 is a front view of the device of Figure 1 with the door in open position.

25 Figure 3 is an enlarged cross-section through the line 3—3 of Figure 2.

Figure 4 is an enlarged top view of the device of Figure 2 with one lid open exposing the powder exit.

30 Figure 5 is a broken view of Figure 4 with the powder lid closed and the other lid open.

Figure 6 is a cross-section through the line 6—6 of Figure 4.

35 Figure 7 is a broken front view with the receptacle lid open.

Figure 8 is a cross-section through the line 8—8 of Figure 7.

Figure 9 is a cross-section through the line 9—9 of Figure 7.

40 Figure 10 is a top view of a modified form of my device with one lid open.

Figure 11 is a cross-section through the line 11—11 of Figure 10.

45 Figure 12 is a top view of another modified form of my device.

Figure 13 is a front view of the device of Figure 12 with the door closed.

Figure 14 is the device of Figure 12 with the door open.

50 Figure 15 is an end view of Figure 14.

Figure 16 is a broken vertical cross-section of Figure 13.

55 The particular form of the device of my invention illustrated in Figures 1 to 9 inclusive comprises a powder casing, or receptacle, having the back 20, the bottom 21, and

the front 22, the latter having an annular recess, 23, within which is a powder puff 24 and a fixedly attached mirror 25. The mirror is maintained in place by means of 60 the angular annular band, or collar, 26, the upper portion 27 of which serves to hold the powder puff in position.

A door, or cover, 28 is hingedly attached to the receptacle at 29 and is retained in 65 closed position by the catch 30.

Hingedly attached to the back 20 at 31 is a lid, or cover, for the receptacle having the bottom 32, which midway of the lid is directed downwardly 33 then transversely 70 34 and then upwardly 35 to form a container for lip pomades, or a similar product, 36 carried by the tray 37, the latter having an extension 38 to facilitate the removal of the tray. The bottom 32 has the opening 39. 75 Abutting upon the upper face of the cover bottom 32 is a closure member 40, movable within the guides 41, 41, and capable of being moved across the opening 39 and closing it. 80

Hingedly attached to the receptacle cover at 42, are two lids 43 and 44, each covering a portion of the receptacle cover, the spring 45 tending to keep these two lids in closed position. 85

The operation of the device is as follows:

Figure 1 represents the device with all containers closed. If it is desired to employ the powder 46 within the powder receptacle, 90 the door 28 is opened as shown in Figure 2 and the powder puff 24 is removed. The cover lid 43 is raised, the slide 40 moved to expose the opening 39 and sufficient powder 46 poured upon the puff 24, the slide moved 95 to closed position.

If the device is in the closed position shown in Figure 1, and it is desired to use the lip rouge 36, the cover lid 44 is opened thus exposing the rouge. 100

It is to be noted that the mirror 25 can be used by opening the door 28 and removing the puff 24.

The modified form of my device shown in Figures 10 and 11 is similar in its main construction to that already described but is modified to carry a lip stick, instead of lip pomade. 105

In this form, the bottom 47 of the receptacle cover does not extend entirely across the powder container, but is interrupted and terminates in an inverted channel portion 110

48. Within the powder receptacle is a lip stick carrying member having the transverse wall 49 and the bottom 50, capable of receiving the lip stick 51. The inverted 5 channel portion 48 of the bottom 47 rests upon the transverse wall 49, thus forming a powder proof jointure.

The operation of this device is similar to that of the device previously described.

10 In the modified form of my device illustrated in Figures 12 to 16 inclusive, the door 52 covering the puff receptacle is hinged 53 at the top portion of the puff receptacle, the inner face of the door being highly polished 15 to act as a mirror. In this modification the powder receptacle is divided into two chambers 54 and 55 by the partition 56, and the bottom member 57 of the receptacle cover is flat and has two openings 58 and 59 into the 20 two chambers 54 and 55. In this construction, the contents of either chamber 54 or 55 may be employed by opening the corresponding cover lids 60 and 61.

It will thus be seen that in my device the 25 powder receptacle may be exposed and access had to the powder without exposing the other toilet articles, and the latter are accessible without opening the powder receptacle. It also carries the necessary powder puffs 30 and a mirror.

My device, therefore, is an efficient attractive, and compact container for the purposes indicated.

I do not limit myself to the particular 35 size, shape, number, arrangement or material of parts as shown and described as these are given simply as a means for clearly explaining the device of my invention.

What I claim is:—

40 1. In a device of the character described, in combination, a receptacle, a cover for the receptacle having an opening therein, a plurality of hinged lids closable over said cover, an exterior recess in one side of the receptacle 45 capable of holding a powder-puff and

a hinged door carried by the receptacle capable of closure over said recess.

2. In a device of the character described, in combination, a receptacle, a cover for the receptacle having an opening therein, means 50 for closing said opening, a plurality of hinged lids closable over said cover, an exterior recess in one side of the receptacle capable of holding a powder-puff and a hinged door carried by the receptacle 55 capable of closure over said recess.

3. In a device of the character described, in combination, a receptacle, a cover for the receptacle having an opening therein, slideable means for closing said opening, a plurality of hinged lids closable over said cover, an exterior recess in one side of the receptacle 60 capable of holding a powder-puff and a mirrored hinged door carried by the receptacle 65 capable of closure over said recess.

4. In a device of the character described, in combination, a receptacle, a cover for the receptacle having an opening therein, a receptacle within said cover, a plurality of 70 hinged lids closable over said cover, an exterior recess in one side of the receptacle capable of holding a powder-puff and a hinged door carried by the receptacle capable of closure over said recess.

5. In a device of the character described, in combination, a receptacle, a cover for the receptacle having an opening therein, a receptacle within said cover, a plurality of 80 hinged lids closable over said cover, an exterior recess in one side of the receptacle capable of holding a powder-puff and a means for closing said opening, a hinged door carried by the receptacle capable of 85 closure over said recess.

Signed at New Rochelle, in the county of Westchester and State of New York, this 25 day of April, 1927.

FREDERICK A. SCHWANNECKE.
